US0D1095307S

(12) **United States Design Patent** (10) Patent No.: **US D1,095,307 S**
(45) Date of Patent: ** Sep. 30, 2025

(54) **RING**

(71) Applicant: **Harry Winston SA**, Plan-les-Ouates (CH)
(72) Inventor: **Rie Yatsugi-Kang**, New York, NY (US)
(73) Assignee: **Harry Winston SA**, Plan-les-Ouates (CH)
(**) Term: **15 Years**

(21) Appl. No.: **29/907,793**

(22) Filed: **Jan. 9, 2024**

(30) **Foreign Application Priority Data**

Jul. 24, 2023 (WO) WIPO135819
(51) LOC (15) Cl. 11-01
(52) U.S. Cl. USPC **D11/34**
